UNITED STATES PATENT OFFICE.

ALEXANDER C. SHAND, OF NARBERTH, PENNSYLVANIA.

TIE-PLATE.

No. 832,630.

Specification of Letters Patent.

Patented Oct. 9, 1906.

Application filed November 18, 1905. Serial No. 283,053.

To all whom it may concern:

Be it known that I, ALEXANDER C. SHAND, a citizen of the United States, residing at Narberth, Montgomery county, State of Pennsylvania, have invented certain new and useful Improvements in Tie-Plates, of which the following is a full, clear, and exact description, reference being had to the accompanying drawings, of which—

10 Figure 1 is a section through a rail, showing my tie-plate as in use in connection with the splice-bars. Fig. 2 is a similar section to Fig. 1, but showing the tie-plate as in use with a rail at a point where there are no splice-bars—that is, at a point remote from the joint between two rails. Fig. 3 is a perspective view of the tie-plate embodying my invention.

15 The object of this invention is to provide a tie-plate for use with railroad-rails which may be used either at a joint between rails in connection with the usual splice-bars or at a point intermediate such joints in connection with the rail.

20 To this end the invention consists in providing the upper surface of the plate with two longitudinally-extending ribs whose inner substantially vertical walls are a distance apart corresponding with the distance from 25 the outer edge of the foot of a rail to the outer edge of the foot of a splice-bar when in use, and the outer of said ribs being of such height as to impinge against a splice-bar foot when in use in connection therewith, 30 the inner rib being of such height that while it serves as a secure stop for the rail-foot will not quite extend to the top thereof at its outer edge, whereby the splice-bar may be seated against the upper surface of the foot 35 of the rail without impinging upon the said inner rib.

The precise character of the invention will be hereinafter pointed out.

In the drawings, A represents a base or 40 body portion comprising a plate adapted to seat upon a tie or sleeper. Extending upwardly from said plate, adjacent one end thereof, is a longitudinally-extending rib B, whose inner wall is substantially vertical, as 45 seen, said rib being of a height to engage the outer edge of the foot of a splice-bar S, of usual construction, as seen in Fig. 1. Also projecting upwardly from said plate A is a 50 second rib C, parallel with said first-mentioned rib and substantially like the latter,

except that the rib C is of a height from the upper surface of the plate A just sufficient to engage the outer edge of the foot of a rail R, and which when the tie-plate is used in connection with splice-bars, as seen in 60 Fig. 1, will be lower than the under surface of said splice-bar foot. The distance apart of the inner walls of said ribs B and C is the distance between the outer edge of the foot of the rail R and the outer edge of 65 the foot of the splice-bar S, whereby when the tie-plate is used at a joint the rib B will engage and support the splice-bar S and the rib C will similarly engage and support the rail R, all as seen in Fig. 1. When the tie- 70 plate is used intermediate of a joint—that is, where the rail is devoid of splice-bars—the rib C alone is in action coming against and so supporting the foot of the rail R, as seen in Fig. 2.

75 The tie-plate A is provided with suitable spike-holes d, d', and d'', the inner wall of the one, d, on the same side of the rail as the ribs B and C being substantially in line with the inner wall of said rib C, as seen, whereby 80 when the spike is driven through said hole into the tie its inner side shall be in contact with the rail-foot, as also is the rib C. When the tie-plate is used at a joint, the spikes will of course pass through the usual slotways in 85 the foot of the splice-bars, as seen in Fig. 1.

The holes d' and d'' on the opposite side of the rail are of course of a distance from the hole d corresponding with the width of the 90 foot of the rail R.

Having thus described my invention, I claim as new and desire to secure by Letters Patent—

1. A tie-plate having two parallel longitudinal ribs on its upper side, the distance 95 apart of whose inner faces is substantially equal to the distance between the side of the foot-flange of a rail and the side of the foot-flange of a splice-bar, when the latter is secured in place to said rail, said plate having a 100 spike-hole between said ribs, the inner edge of which spike-hole is in line substantially with the inner face of the inner one of said ribs, substantially as set forth.

2. A tie-plate having two parallel, longitudinal ribs on its upper side, the distance 105 apart of whose inner faces is substantially equal to the distance between the side of the foot-flange of a rail and the side of the foot-flange of a splice-bar, when the latter is se- 110

cured to said rail, the inner one of said ribs being somewhat less in height than the distance from the under side of the foot-flange of the splice-bar adjacent the outer edge of the rail-foot-flange, to the upper surface of the tie-plate, substantially as set forth.

3. A tie-plate having two parallel, longitudinal ribs on its upper side, the distance apart of whose inner faces is substantially equal to the distance between the side of the foot-flange of a rail and the side of the foot-flange of a splice-bar, when the latter is secured to said rail, the inner one of said ribs being less in height than the distance from the under side of the foot-flange of the splice-bar adjacent the outer edge of the foot-flange of the rail to the upper surface of the tie-plate, said plate having a spike hole or holes, whose inner side is a distance from the inner side of the inner of said ribs substantially equal to the width of the foot-flange of said rail, substantially as set forth.

4. A tie-plate having two parallel, longitudinal ribs on its upper side, the distance apart of whose inner faces is substantially equal to the distance between the side of the foot-flange of a rail and the side of the foot-flange of a splice-bar, when the latter is secured to said rail, the inner one of said ribs being less in height than the distance from the under side of the foot-flange of the splice-bar adjacent the outer edge of the foot-flange of the rail to the upper surface of the tie-plate, said plate having a spike hole or holes, whose inner side is a distance from the inner side of the inner of said ribs substantially equal to the width of the foot-flange of said rail, substantially as set forth.

In testimony whereof I have hereunto affixed my signature.

ALEXANDER C. SHAND.
